UNITED STATES PATENT OFFICE.

WILLIAM TIETZ, OF RICHMOND, VIRGINIA; R. GRAYSON DASHIELL CURATOR OF THE ESTATE OF SAID WILLIAM TIETZ, DECEASED.

SECTIONAL SHELVING.

1,063,086.

Patented May 27, 1913.

Application filed January 19, 1912. Serial No. 672,071.

To all whom it may concern:

Be it known that I, WILLIAM TIETZ, a citizen of the United States, residing at Richmond, in the county of Henrico and 5 State of Virginia, have invented new and useful Improvements in Sectional Shelving, of which the following is a specification.

This invention relates to improvements in sectional shelving and its leading object is 10 to provide a shelving construction comprising a plurality of units capable of indefinite multiplication and connected together by improved locking joints.

Another object of the invention is to provide 15 a sectional shelving having vertical supporting members provided with locking flanges and a back panel having flanges adapted to interlock with said locking flanges.

Another object of the invention is to provide 20 a shelving construction including a plurality of vertical front supporting members having converging locking flanges and a plurality of front members having grooves 25 adapted to slidably interlock with the locking flanges.

Another object of the invention is to provide 30 a shelving construction including vertical supporting members, shelf sections supported thereby and improved means for locking the adjacent ends of said shelf sections.

A still further object of the invention is 35 to provide improved corner locking means for tying the end panels to the back and front members.

A still further object of the invention is 40 to provide improved means for supporting the shelf sections in adjustable positions.

With the above and other objects in view, 45 the invention consists in certain combinations, constructions and arrangements of parts clearly described in the following specification and clearly illustrated in the accompanying drawings, in which:

Figure 1 is a front elevation of the improved shelving construction; Fig. 2 is a horizontal sectional view taken on line 2—2 of Fig. 1; Fig. 3 is a vertical sectional view 50 taken on line 3—3 of Fig. 1; Fig. 4 is a vertical longitudinal view taken through the

central part of the construction; Fig. 5 is a detail view on an enlarged scale partly in elevation and partly in section showing the track and runners for the doors; Fig. 5^a 55 is a plan view of the door runner; Fig. 6 is a perspective view of one of the end panels; Fig. 7 is a detail horizontal sectional view showing one of the corner locking bars; Fig. 8 is a detail elevation of one of the rear corner locking bars; Fig. 9 is a detail enlarged section thereof; Fig. 10 is a detail perspective view of one of the locking arms carried by the end panel; Fig. 11 is a detail sectional view showing one of the locking elements secured to the shelf sections; Fig. 12 is a detail sectional view 60 showing holding lugs of one of the horizontal shelf supporting sections or members; Fig. 13 is a detail sectional view showing one of the locking pins; Fig. 13^a is a perspective view of one of the locking pins; Fig. 14 is a detail vertical sectional view showing the upper tracks for the sliding doors; Fig. 15 is a bottom plan view showing 65 the improved shelf adjusting means and shelf section tying means; Fig. 16 is a transverse sectional view taken on the line 16—16 of Fig. 15; Fig. 17 is a detail longitudinal sectional view taken on the line 17—17 of Fig. 15; Fig. 18 is a bottom plan view of a modified form of the shelf adjusting means; Fig. 18^a is a sectional view of a modified 70 form of the stationary supporting members; Fig. 19 is a detail vertical sectional view of one of the stationary vertical members of the shelf adjusting construction shown in Fig. 18; Fig. 20 is a detail perspective view 75 of a shelf brace; Fig. 21 is a vertical sectional view of a bracket; Fig. 22 is a front elevation thereof; Fig. 23 is a detail view of the upper end of one of the members of the bracket construction shown in Figs. 21 and 22; Fig. 24 is a detail horizontal sectional view showing a modified form of one 80 of the front supporting members; and, Fig. 25 is a detail vertical sectional view taken on line 25—25 of Fig. 4; Fig. 26 is a detail plan view partly in section showing a modified shelf section tie.

In the accompanying drawings I have illustrated a sectional shelving construction com-

prising two units interlocked to form a single casing, but it is understood that any number of units may be similarly interlocked, and each of the units may be of different lengths.

Referring to the drawings 5 denotes the front central supporting member, which joins the two units. This member is shown to be formed of wood, or like material, and 10 is provided with two longitudinal grooves 5', which are arranged in outwardly diverging relation, and which are adapted to interlock with the outwardly converging locking flanges 6 of the supporting bar or member 15. This member or bar is formed of folded sheet metal to provide an inner contacting pair of sides 8, which are formed with a series of vertically spaced openings 9, through which the locking pins 10 (not shown) are adapted to be passed for holding the horizontal shelf supporting members 11.

The horizontal shelf supporting members 11 are formed of folded sheet metal to provide sockets 12 and angular flanges 13, on which the wooden or other shelf sections are disposed. The flanges 13 are stamped to provide vertical locking lugs or tongues 14, which are disposed in contacting pairs, as shown in section in Fig. 12 and in plan in Fig. 2. The intermediate horizontal shelf supporting members 11 are connected at their rear ends to the vertical supporting member or bar 15, which is formed of folded sheet metal to provide a shelf supporting portion 16 and inwardly curved flanges 17, the edges of which are arranged in confronting relation and are adapted to interlock with the inner ends of the back panels 18 and 19. The inner ends of said back panels are formed with hook flanges 20, which slidably interlock with the curved flanges 17, as shown in Fig. 2, in section. The outer ends of said back panels 18 and 19 are formed with similar hook flanges 21, which slidably interlock with the inwardly curved flanges 22 of the rear end corner supporting bars or members 23. The end corner bars or members 23 are also formed of folded sheet metal and are shaped to provide an inwardly projecting shelf supporting portion 24 and a lateral hook flange 25, the central portion of which is flattened to provide a longitudinal tongue 26, which is adapted to slidably fit in the vertically disposed end located groove 27 of the end panel 28. The front portions of the end panels 28 are held in locked relation by the front corner bars or supporting members 29, which are also formed of folded sheet metal and are shaped to provide outer hook flanges 30, the central portions of which are flattened to form tongues 31, which are adapted to fit in the grooves 32 of the end panels, like the tongues 26 of the rear cor-

ner bars 23. The front corner supporting bars or members 29 are further formed with an inwardly inclined locking flange 33, offset from the shelf supporting portions 34 thereof, and disposed in converging relation 70 to the inclined flanges 35, which extend from the tongues 31. The locking flanges 35 are formed, as well as the locking flanges 25 of the rear corner bars 23, with vertically spaced slots 36, which are adapted to receive the locking arms or lugs 37 carried by the end panels 28, which are shown in Figs. 6 and 10 in perspective. The arms or lugs 37 are formed with notches 39 which receive the lower edge portions of the slots 36, 80 as shown in plan in Fig. 7. The end panels 28 are provided with transverse cleats 40, which carry small arms 41, which are formed with openings 42, which are adapted to receive the lugs or pins of the end 85 shelf supporting members 11.

Vertical wooden bars or members 43, which are formed with converging slots, are interlocked with the corner bar flanges 33 and 35. Bottom shelf sections 44 are arranged between the central or intermediate supporting bars 7 and 15 and the end bars, the front edge portions of said bottom shelf sections being extended to lie in the same plane as the front faces of the front members 5 and 43. Top shelf sections 45 are likewise arranged between said central or intermediate bars and the corner bars. 95

The front upper portions of the lower shelf sections 44 are provided with sliding door tracks 46, and the top shelf sections are provided with sliding door tracks 47. Sliding doors 48 operate on said tracks 46 and 47. A view of the track construction is shown in section in Fig. 14. Each track 100 consists of a strip of sheet metal which is folded to provide U-shaped track portions 49 which are held spaced apart by a central arched connecting portion 49'. By this arrangement a single metal strip forms two 105 independent door tracks and a single row of fasteners or screws extended through said central portion 49' will securely hold the two tracks. In place of wheels I employ runners 50, which are fixed to the doors. 110 Each of these runners consists of a metal strip formed to provide a longitudinal channel 51 and lateral flanges 52. Each runner is provided with a central arch 53 which provides a minimum contact surface 115 for engagement with the track on which it operates. Each runner is further formed with a longitudinal slot 54 located in one end portion thereof and which interlocks with a screw 54' secured to the door. The 120 opposite end portion of the runner is provided with a spring catch 55 which is rigidly secured to the bottom wall of the channel 51 and has its end portions extended outwardly of the end of the runner and 125 130

formed into spring coils 56 which terminate in biting prongs 57, which are adapted to be pressed into the side wall of the channel formed in the upper and lower edges of each door, thereby holding the runner securely in place. By pressing the coils 56 toward each other the biting prongs 57 may be disengaged from the side walls of the door channels and the door easily removed.

10 The manner in which the runners contact with the door tracks is shown in section in Figs. 5 and 14 and in elevation in Fig. 5. 53' designates a glass bearing point.

The shelf sections are formed with recesses 58 located in the end portions thereof and which receive the dished or concaved flanges 59 of the locking members 60 which are held in position by a single screw 61. By forming the flanges 59 concave biting edges 59' are provided which are adapted to bite into the walls of the recesses 58. The locking members for the upper shelves are shown in Fig. 11 and in Fig. 4 and are of angular design, while the locking members 25 for the intermediate shelf sections and the lower shelf sections are shown in Fig. 12 and are not angular. The shelf supporting members 11 are held in adjusted position by means of locking pins or oblong keys 62 which are provided with heads 62' having recesses 62'' to receive the point of a screw driver or like instrument whereby pins can be readily lifted out of place. The pins fit snugly in the oblong openings 9 formed in 30 the inwardly projecting supporting portions of the vertical front and rear bars 7 and 15, and slidably supporting the structure against relative movement.

In order to securely unite the adjacent edges of the shelf sections arched bridge plates 63 are provided, these bridge plates being held in place by fastening devices which extend into the sockets formed by the horizontal shelf supporting sections.

45 Two forms of fastening devices are employed, one form is illustrated in the central portion of Fig. 4 wherein a screw bolt 64 extends through the socket of the horizontal shelf supporting section 11 and is secured in place by a nut 65. The other form is illustrated in the lower portion of the same figure and comprises an upper and a lower screw bolt 66 which are held in clamping relation by means of a connecting female screw 67.

In order to strengthen the rear panels 19 without increasing the amount of material usually required by corrugating, I form said panels with a series of parallel slots and offset tongues 67 and secure arched reinforcing strips or ribs 68 in said slots by forcing the tongues 67 in clamping positions and I arch said tongues in order to increase their clamping action and to strengthen their connection between the ribs and the panels

The wooden front bars or members 5 may be dispensed with and the front supporting members 7 and 30 formed with interlocked front flanges 69 and 70, the interlocking being preferably effected by curving the edge portions of the flanges to provide engaging hooks, as shown in section in Fig. 24.

In Figs. 15, 16 and 17 means for securely uniting the engaging edge portions of shelf sections and of adjusting the elevation of the shelf sections are shown. In this construction, a stationary member 71 is provided, this member being formed to provide three channels. The wall of the central channel 72 forms the means for securing the member to a suitable support and is provided with openings to receive screws or other fasteners. The central walls of the channels on either side of the channel are provided with vertically spaced openings 73, the openings being arranged in horizontal alinement. The central wall 72 is provided with an offset eye 74 which is engaged by a tongue 75 carried by the adjusting member 76 and tie 76. The adjusting member and tie 76 is provided with angular flanges 77 which are adapted to be fitted snugly in grooves formed in the under side of the shelf sections 78, as shown in section in Fig. 16. The adjusting and tie member 76 is formed with longitudinally spaced eyes 79, which are offset to provide guides for the arms 80 of the latch 81. This latch is preferably formed of wire and its central portion is contracted to form a handle 82, which is offset from the arms 80 so as to be readily grasped. The latch 81 is provided with an angular portion 83 forming a stop which is adapted to engage a stop 84 carried by the adjusting member or plate 76. The central portion of said adjusting member or plate 76 is formed with a channel and the central wall of said channel is provided with small recesses 85 in which the inturned arms or portions of the latch 81 are adapted to snap so as to hold said latch in its locking position. The terminals of the arms 80 are adapted to project through the openings 73 and the stationary member 71. The plate 76 is further formed with angular arms 87 which are formed to provide hooks 88 adapted to interlock with the lower edges of said openings 73 formed in the stationary members 71, as shown in Fig. 17. A joint plate 89 bridges the upper edge portions of the shelf sections 78 and is suitably secured thereto and is provided with a hook 90 on its inner end which is adapted to interlock with the stationary member 71. The hooks 88 are adapted to prevent the shelf sections 78 from dropping and the latch 81 is adapted to hold said hooks 88 in locked position. A brace 91 is secured to one of the sections 78 and is formed with an angular upstand- 130

ing arm having an offset hook 92 adapted to interlock with the stationary member 71, as shown in Figs. 16 and 17. The plate 76 is held in locked relation with the shelf sections by means of pivoted plates or latches 93 which are adapted to swing over said plate and prevent the displacement of the embedded flanges 77.

Fig. 18 shows a modified form of the shelf supporting and adjusting means, in which end supporting members 94 are provided, said members being of similar design to the members 71 with the exception that the openings therein are shaped differently, the central wall of the central channel having a series of offset tapering sockets 95 which are adapted to receive the locking tongues 96 adjustable in the central channel 97 of the tie plate 98. The central wall of the channel 97 is provided with longitudinal slots 99 located near the ends thereof and the tongues 96 are provided with pins 100 which slidably extend through said slots. The plate or member 98 is provided with longitudinally spaced eyes 101 which form guides for the side arms 102 of the latches 103. The ends of the side arms 102 are bent to provide stops 102' which are adapted to be held in adjusted positions in the openings 104. This arrangement permits of a relative movement between the end supports and the shelves and avoids spilling of the contents of the shelves should the joints between the end supports and the shelves become very wide.

In Figs. 21, 22, and 23 an adjustable bracket construction is shown comprising a stationary supporting member 105, which is formed with a series of vertically spaced openings 106 arranged in horizontal alignment. The member 105 is secured in place by screws or fastening means extended through the central portion thereof. The bracket consists of an angular bracket member 107 which has its upper horizontal leg braced to its lower vertical leg by a brace rod 108. The vertical leg of the bracket member 107 provided with rearwardly offset tongues 109 which are adapted to removably fit in the openings 106 and hold said bracket in various positions upon the support 105.

The stationary member 71 and the member 105 may be formed with a single vertical series of openings instead of a double vertical series, if such construction is found desirable.

Fig. 26 shows a modified tie for locking two shelf sections together. This tie consists of a plate 110 which is provided with longitudinally spaced lateral ears 111 and is inserted in registering slots formed in the engaging edges of shelf or board sections, screws or fasteners being extended through said ears 111.

I claim:—

1. A sectional shelving construction including vertical supporting bars adapted to support shelves and formed to provide outwardly converging locking flanges, and 70 grooved facing members interlocking with said flanges.

2. A sectional shelving construction including vertical supporting bars formed of folded sheet metal and adapted to support shelves and formed with outwardly converging locking flanges and facing members having slots interlocking with said flanges. 75

3. A sectional shelving construction including vertical supporting bars formed of folded sheet metal to provide outwardly converging locking flanges and grooved facing strips slidably interlocked with said flanges. 80

4. A shelving construction comprising vertical supporting bars adapted to support shelves and formed of folded sheet metal to provide locking flanges and tongues, facing strips interlocked with said flanges and end panels interlocked with said tongues. 90

5. A sectional shelving construction including vertical bars adapted to support shelves and formed of sheet metal folded to provide inturned flanges, one of said flanges being formed to provide a tongue and panels having hook flanges interlocking with a part of said inturned flanges. 95

6. A sectional shelving construction comprising vertical supporting bars provided with means for adjustably supporting shelves and formed with tongues, panels having grooves to receive said tongues and locking arms interlocking with said bars. 100

7. A sectional shelving construction comprising vertical supporting bars formed from folded sheet metal to provide inwardly extending shelf-supporting portions, and shelf sections arranged on said portions with their ends in adjacent position and 110 secured in locked engagement to each other. 105

8. A sectional shelving construction including shelf supporting means, independent shelf sections arranged on shelf supporting means and interlocked therewith and 115 bridge plates holding said sections in interlocked relation with said supporting means.

9. A sectional shelving construction including shelf supporting means, shelf sections arranged on said supporting means 120 with ends in confronting relation and interlocked with said supporting means and plates bridging said confronting ends and secured to said supporting means.

10. A sectional shelving construction 125 comprising vertical supporting bars, horizontal shelf supporting bars secured to said vertical supporting bars and provided with upstanding locking lugs and shelf sections having locking lugs formed with openings 130

to receive the first locking lugs and to hold said sections into interlocked relation with the shelf supporting bars.

11. A shelving construction including vertical supporting bars formed of folded sheet metal to provide inwardly projecting shelf supporting portions and having confronting hook flanges and back panels having hook flanges slidably interlocking with said first hook flanges. 70

12. A shelving construction including shelf sections having recesses near their end portions, supports for said shelf sections having connecting pins, and concaved convex plates disposed in the recesses and provided with means interlocking with said pins, the edges of said plates being adapted to bite into the walls of the recesses. 75

13. A supporting bar for shelving construction consisting of sheet metal folded to provide shelf supporting portions and flanges extending laterally thereof and terminating in interlocking hooks disposed on the front side thereof. 80

14. A shelving construction consisting of vertical supporting bars and horizontal supporting bars connected thereto, shelf sections mounted upon said horizontal supporting bars with their inner ends disposed in confronting relation, means interlocking said confronting ends to the adjacent supporting bars, and means bridging said confronting ends and secured to said adjacent supporting bars. 85

15. A shelving construction including a plurality of vertical supporting bars having inwardly projecting flattened portions, and outwardly converging locking flanges and a plurality of horizontal bars having bifurcated ends straddling said flattened portions and secured to said vertical supporting bars. 90

16. A shelving construction consisting of a plurality of vertical bars having inwardly projecting flattened shelf-supporting portions and outwardly converging locking flanges and a plurality of horizontal supporting bars formed of sheet metal folded into T-shape in cross section and secured in interlocking relation with the flattened portions of said vertical bars. 95

17. A shelving construction including vertical supporting bars and horizontal bars detachably connected therewith and holding said vertical bars in spaced relation, the horizontal bars being formed to provide longitudinal sockets and lateral shelf supporting flanges, said flanges being spaced from each other, shelf sections having their ends locked to said horizontal bars, arched plates bridging the joints between said sections, and fastening devices extending through said plates and through the sockets and secured to said horizontal bars. 100

18. A shelving construction including ver-

tical and horizontal supporting bars connected in spaced relation, the horizontal supporting bars being formed of sheet metal and folded to provide lateral shelf supporting flanges, portions of said flanges being formed with vertical pins, and shelves having their ends disposed on said flanges. 105

19. A shelving tie consisting of a plate having vertical longitudinal flanges adapted to be fitted in grooves formed on the under-face of the shelf sections to bridge the joint between the engaging edge portions of the sections, and means for holding said flanges in locked position. 75

20. A shelf tie consisting of a substantially U-shaped plate adapted to bridge the joint between engaging shelf sections, the vertical flanges of said plate being adapted to be snugly fitted in grooves formed on the under-side of the shelf sections and latches pivoted to said shelf sections and adapted to engage the horizontal flanges of the plate to hold the vertical flanges in said sections. 85

21. A shelf tie consisting of a plate having vertical portions, shelf sections having slots located near the edges thereof to receive said vertical portions and latches pivoted to said shelf sections for holding said vertical portions in said slots. 90

22. In combination, a tie plate adapted to bridge the joint between the engaging shelf sections and to hold the sections in locked relation, a latch slideable on said plate for adjusting the elevation of the shelf sections and a stationary member co-operating with said latch and plate to support said shelf sections. 95

23. In combination, a plate adapted to bridge the joint between the engaging shelf sections and to be secured to said sections, a latch slideably connected with said shelf and provided with an arm adapted to be moved outwardly of said plate, and a stationary member having an opening to receive said arm. 100

24. In combination, a plate adapted to be secured to a shelf and provided with longitudinally spaced eyes and a terminal hook flange, a latch having side arms slideable through said eyes and outwardly of the outer end of said plate, and a stationary member having an eye to receive the hook flange and openings to receive the ends of the latch arms. 110

25. In combination, a plate adapted to be secured to a shelf, a latch having side arms slideable on said plate, a supporting hook extending from one end of said plate, and a supporting member having spaced channels the central walls of which are provided with openings to receive the ends of said arms and having an eye to receive the supporting hook. 120

26. In combination, a stationary shelf supporting member formed of sheet metal 130

to provide spaced channels the central walls of which are formed with vertical spaced openings, adjusting means adapted to lock engaging shelf ends and coöperating with 5 said openings in said stationary member to support a shelf, an arched bridge plate secured at the joint of said sections and having hook interlocking with said stationary supporting member.

10 27. In combination, stationary shelf supports, and plate secured to and adapted to support a shelf on said stationary supports and to permit of a relative movement between the shelf and said supports, and means 15 carried by the plate and coöperating with said stationary member to lock said supporting means.

28. In combination, a stationary member having a plurality of vertically spaced sock-

ets, a plate adapted to be secured to a shelf, 20 a tongue adjustable on said plate and adapted to be inserted in said sockets, and a latch carried by said plate adapted to engage said stationary member.

29. In combination, stationary shelf supporting members, a plate adapted to be secured to a shelf, latches slidable upon said plate and having angular ends adapted to be connected with said supporting members, and tongues slidable upon said plate 30 and adapted to be connected to said stationary members.

In testimony whereof I affix my signature in presence of two witnesses.

WILLIAM TIETZ.
